DESIGN FOR A TUNIC BLOUSE

Josef Walker, New York, N. Y.

Application December 18, 1944, Serial No. 116,954

Term of patent 3½ years

(Cl. D3—25)

To all whom it may concern:

Be it known that I, Josef Walker, a citizen of the United States, residing in New York city, in the county of New York and State of New York, have invented a new, original, and ornamental Design for a Tunic Blouse, of which the following is a specification, reference being had to the accompanying drawing, forming part thereof.

Fig. 1 is a front view of a tunic blouse showing my design, and

Fig. 2 is the rear view thereof.

I claim:

The ornamental design for a tunic blouse, substantially as shown.

JOSEF WALKER.
